IGNITION COMPOSITION

Lawton A. Burrows, Wenonah, N. J., assignor to
E. I. du Pont de Nemours & Company, Wil-
mington, Del., a corporation of Delaware

Application July 30, 1937, Serial No. 156,483

12 Claims.

(CL. 52—2)

The present invention relates to blasting initiators, and in particular to new and improved ignition compositions for use in various types of said initiators.

As is well known, ignition compositions for use in blasting initiators generally, must be highly sensitive to heat in order to give effective performance. Unfortunately, the materials known to the art which possess this required sensitivity to heat, likewise tend to be sensitive to shock, friction or static charges. Consequently, such materials are hazardous and present serious problems, not only during the course of manufacture, but in the handling of the finished product thereafter.

Furthermore, the ignition compositions known to the art are frequently unsatisfactory for the reason that they are incompatible with certain of the metals and alloys commonly employed for initiator shells, and have a corrosive effect on said shells.

The object of my invention is to provide a new and improved ignition composition which is relatively insensitive to shock, friction and static electricity. A further object is to provide such a composition which is satisfactory for use with the metals and alloys commonly employed for initiator shells. A still further object is to provide an ignition composition which is readily ignited and possesses uniform and rapid burning properties. Other objects will be discussed as the invention is further described hereinafter.

I have found that these objects are accomplished according to the present invention, by the preparation of ignition compositions comprising calcium hypophosphite and an oxidizing agent. While I find that satisfactory ignition compositions are formed from calcium hypophosphite and an oxidizing agent alone, I prefer to employ compositions comprising calcium hypophosphite, an oxidizing agent, and at least one readily ignitable fuel. Many different types of fuels are suitable including both organic and inorganic fuels. As examples of organic fuels, I may employ ground smokeless powder and the like. As inorganic fuels, I prefer to employ finely divided atmospherically stable metals such as magnesium, zirconium, and aluminum, atmospherically stable alloys such as antimony-iron, ferro-silicon, silicon-manganese carbon, calcium silicide, and metalloids of group VI of the periodic table.

Preferred ignition compositions according to my invention and preferred adaptations of the same to the various types of blasting initiators, are set forth in the following examples. It is

understood, however, that the compositions indicated constitute merely preferred embodiments of my invention for the purpose of more adequate illustration, and that the scope of the invention is not to be limited by the details set forth in these examples.

Example I

	Per cent
Potassium chlorate	30 10
Calcium hypophosphite	30
Pyro smokeless powder	40

This composition is desirably employed as a loose ignition charge in the various types of blasting initiators. It may be grained according to any of the well known procedures in order to facilitate loading into the initiator shell.

Example II

	Per cent
Calcium hypophosphite	45 20
Potassium nitrate	45
Sulfur	10

This composition is likewise highly desirable as a loose charge in blasting initiators generally.

Example III

	Per cent
Calcium hypophosphite	40
Potassium chlorate	40
Calcium silicide	20 30
Nitrostarch	

The foregoing composition is especially suitable as an ignition composition for initiators of the concave plug type. An inappreciable amount of nitrostarch is employed as a binder and to accomplish the partial gelatinization of the composition. Any of the solvents commonly employed for such purpose may be used to assist in this gelatinization. The resulting compositions show no tendency to become friable or to disintegrate on storage, but remain in position in the concave plug, as a compact coherent mass.

In the manufacture of electric squibs, I prefer to employ a pressed base charge consisting of calcium hypophosphite, potassium chlorate, and at least one of the metallic or alloy fuels mentioned in the foregoing, such as magnesium, calcium silicide or the like. This base charge is preferably ignited by means of a loose superposed charge consisting of calcium hypophosphite and potassium chlorate.

By way of more exact description, reference is made to the accompanying drawing, in which Fig. 1 shows an ordinary fuse type blasting cap.

Fig. 2 shows an electric blasting cap of the concave plug type, while Fig. 3 shows an electric squib of the closed type. Similar numerals refer to similar parts throughout the several views.

5 Referring to Fig. 1, 1 designates the shell of the initiator which is made of gilding metal or other suitable material, 5 the base charge preferably tetryl, 4 a primary charge, e. g. mercury-fulminate enclosed in the capsule 3, said primary 10 charge being superimposed on the base charge. 2 represents the ignition composition of my invention, which composition is to be fired by the flame from a fuse. Referring to Fig. 2, the ignition composition 2 of the present invention is shown 15 in a concave plug 9, in close relationship with the primary charge 4, which is superimposed on the secondary charge 5. The ignition composition 2 is fired by means of an electric current passing through the leading wires 6, bringing to incandescence the bridge wire 10 which passes thru the ignition composition. The leading wires are held in place by means of the conical bridge plug 9, with the waterproofing composition 8 above the bridge plug and the sulfur composition 7 at the 20 top. Fig. 3 shows an electric squib having the loose ignition composition 2, superimposed on a pressed base charge 11, which preferably includes calcium hypophosphite, a fuel and an oxidizing agent. The ignition composition 2 is fired by 25 electrically heating the bridge wire 10, to incandescence.

It is apparent from the foregoing that the calcium hypophosphite-containing compositions according to the present invention are satisfactorily 30 adapted for use as ignition compositions in the various types of blasting initiators. The presence of the calcium hypophosphite as a chief ingredient imparts to the resulting composition the highly desirable properties of low sensitiveness to 35 shock and friction, but without any diminution in the ability of said composition to ignite readily and burn uniformly and rapidly.

Accordingly, the adoption of calcium hypophosphite as a principal ingredient in ignition compositions according to the present invention 40 materially reduces the hazard pertaining in the manufacture and handling of the various initiating devices in which said compositions are employed.

It is understood that the various examples cited herein are given by way of illustration. Many variations may be made without departing from the spirit and scope of my invention. For example, the composition recited for use in a 5 concave plug is suitable not only as the ignition composition of a blasting initiator, but also as the ignition composition of a delay squib. I therefore, intend to be bound only by the following claims. 10

I claim:

1. An ignition composition comprising calcium hypophosphite and an oxidizing agent.
2. An ignition composition comprising calcium hypophosphite, an oxidizing agent and a fuel. 15
3. An ignition composition comprising calcium hypophosphite, an oxidizing agent and an inorganic fuel.
4. An ignition composition comprising calcium hypophosphite, an oxidizing agent and an atmospherically stable metal. 20
5. The ignition composition of claim 4 wherein in the atmospherically stable metal comprises magnesium.
6. An ignition composition comprising calcium 25 hypophosphite, an oxidizing agent and an atmospherically stable alloy.
7. The ignition composition of claim 6 wherein in the alloy comprises calcium silicide.
8. An ignition composition comprising calcium 30 hypophosphite, an oxidizing agent and a metalloid of group VI of the periodic table.
9. The ignition composition of claim 8 wherein the metalloid comprises sulfur.
10. An ignition composition comprising calcium 35 hypophosphite, an oxidizing agent and an organic fuel.
11. The ignition composition of claim 10 wherein the organic fuel comprises ground smokeless powder. 40
12. An electric squib which includes a base charge comprising calcium hypophosphite, an oxidizing agent and a readily ignitable inorganic fuel, and a superposed ignition charge comprising calcium hypophosphite and an oxidizing agent.

LAWTON A. BURROWS.
